BASTING BRUSH

Lawrence R. Schumann, 302 Beacon St., Boston, Mass.

Filed Feb. 24, 1960, Ser. No. 59,500

Term of patent 14 years

(Cl. D9--2)

Fig. 1 is a view in elevation of a basting brush showing my new design.

Fig. 2 is an enlarged top plan view thereof with the handle fragmentarily shown for convenience of illustration, and

Fig. 3 is an enlarged side elevational view thereof as shown in Fig. 2.

The dominant features of this invention reside in the portions shown in full lines.

I claim:

The ornamental design for a basting brush, substantially as shown and described.
